United States Patent Office

Des. 185,513
Patented June 16, 1959

185,513

PLAYGROUND DEVICE

Martin Rosenzweig, Williston Park, and Harold Krisel, Queens Village, N.Y., assignors to Aluminum Company of America, Pittsburgh, Pa., a corporation of Pennsylvania

Application January 20, 1958, Serial No. 49,310

Term of patent 3½ years

(Cl. D34—5)

Fig. 1

Fig. 3

Fig. 1 is a top plan view of a playground device showing our new design;

Fig. 2 is a side elevation of Fig. 1;

Fig. 3 is an enlarged end elevation viewed from the right of Fig. 2; and

Fig. 4 is an enlarged end elevation viewed from the left of Fig. 2.

We claim:

The ornamental design for a playground device, substantially as shown.
